A. McCarter
 Car Coupling
 № 63,277. Patented Mar 26, 1867

 Arthur McCarter

United States Patent Office.

ARTHUR McCARTER, OF LANCASTER, PENNSYLVANIA.

Letters Patent No. 63,277, dated March 26, 1867.

IMPROVED CAR-COUPING.

The Schedule referred to in these Letters Patent and making part of the same.

TO ALL WHOM IT MAY CONCERN:

Be it known that I, ARTHUR McCARTER, of Lancaster, in the county of Lancaster, and State of Pennsylvania, have invented a new and improved combination in the construction of Self-Acting Couplings for Railroad Cars and the like; and I do hereby declare that the following is a full and exact description thereof, reference being had to the accompanying drawings, making a part of this specification, in which—

Figure 1 is a perspective view of one of the coupling-boxes, A, with a link, G, shown in the flaring mouth, E.

Figure 2, a vertical section of two such boxes and link.

Figure 3, portion shown in perspective, seen from behind the flared mouth.

Figure 4, a section of a short box, with the swinging pin drawn out.

Figure 5, detached views of the swinging pin, C, and yielding stand-post, F, showing the link-notch, g, and sliding shoulders, f.

The nature of this invention consists in the device of an efficient, self-acting coupling, which will obviate the necessity of getting between the cars in the operation, often proving fatal, in coupling cars in the ordinary manner. I am aware, also, that numerous devices with this view have been patented, but none have been extensively adopted by railroad companies, owing to some objection or defect in their operation, which it is designed to remedy by this combination of parts.

To enable others skilled in the art to make and use my invention, I will briefly describe its construction (clearly shown) and operation.

The casing, A, may be made of wrought or cast iron, with a pair of standards, B B', with slot and terminal recess, D D', in which the cross-arm, d, on the pin C, slides, or is lodged in the recess D', suspending the key or pin C between the standards B B'. The oval-widened and flaring mouth, E, with its guide or side wings, E', forms the bull-nose or buffer, guiding the link in forming a connection. The stand-post, F, may terminate the box, and be permanently affixed, or made with shoulders, f, for sliding in a slot made in the upper and lower side of the extended casing, A. This stand-post, F, in either case has a deep notch, g, fig. 5, with rounded lips, for the reception of the end and support of the link, to keep it horizontal when coupling. The object of having a sliding stand-post, F, with a coiled spring, H, to act against, is to prevent injury to the end of the link when thrust back with too much force. The side extension, E', of the mouth guides the link into the notch and prevents a lateral motion. The operation is illustrated by fig. 4, which shows the link supported in the notch and lip of a short box. The pin C may be down or hanging in the recess as shown, since the least concussion of the buffers or links will dislodge it, so as to drop down through the opening of the link G. In the long case, the pin C is shown down, swinging by its arm, d, in the vertical slots, D, of the standards, B B', and as the link enters it lifts the end of the pin till its rounded end has passed under it and strikes the notch of the stand-post, F, when the swinging pin drops between the opening of the link, and the jar will cause the pin of the opposite casing to drop, if not previously in that position, and the coupling will be complete and effectual without attention to the parts at the time. For uncoupling, the pin is drawn out or upwards in the slotted standards, and either suspended vertically or laid back, as shown in fig. 4. It will be seen that this arrangement is equally well adapted to the use of short or long links, and can readily be applied to ordinary couplings now in use.

I am aware that I. H. Parson's car-coupling, patented February 13, 1866, has a closed shell, and bars that slide up and down in slots cut in the sides of the shell. These bars are connected at the top to the pin, with other fixings contrived with a view to the same end, differing, however, in several important points. This is the case when contrasted with the one hundred and forty-one couplings granted since 1861. I do not find a case with a slotted top and bottom, having vertical standards and its sides open, except where the prolonged side-pieces E' of the mouth form guides as stated; nor do I find a stand-post, either firm or yielding, with a link-bearing notch, to hold the link in a horizontal position; nor do I find a pin with a cross-arm operating in slotted standards in the manner described.

What I claim as my invention, and desire to secure by Letters Patent, is—

The combination and arrangement of the slotted casing, A, with its vertical standards, B B', cross-arm, d, of pin, C, when operating in a vertical slot, D, with a terminal recess, D', together with a stationary or yielding stand-post, F, with its link-notch, g, all arranged and operating in the manner and for the purpose specified.

I also claim the cross-arm, *d*, on the pin *C*, in combination with the upright standards, *B B'*, when slotted in the manner and for the purpose shown.

I also claim the yielding stand-post, *F*, with its link-slot, in combination with the coiled spring, *H*, constructed and operating in the manner shown for the purpose described.

I also claim the prolongation or jaws, *E'*, of the flared mouth, *E*, in combination with the open case, *A*, when constructed in the manner and for the purpose shown and set forth.

ARTHUR McCARTER.
